DISPENSER TOP FOR A PRESSURE CONTAINER

William C. Harris, Racine, Wis., assignor to S. C. Johnson & Son, Inc., Racine, Wis.

Filed Sept. 27, 1963, Ser. No. 76,771

Term of patent 14 years

(Cl. D58—26)

Fig. 1.

Fig. 2.

Fig. 3.

Fig. 4.

FIG. 1 is a front elevational view of a dispenser top for a pressure container embodying my new design;

FIG. 2 is a side elevational view;

FIG. 3 is a rear elevational view;

FIG. 4 is a top perspective view thereof;

FIG. 5 is a top plan view of a dispenser top.

The portions shown in broken lines are for illustrative purposes only.

I claim:

The ornamental design for a dispenser top for a pressure container, substantially as shown and described.
